HOLDER FOR SCREWS

Ernest L. Dahlquist, Auburn, Iowa

Application July 13, 1938, Serial No. 219,060

9 Claims. (Cl. 81—18)

The present invention relates to a tool especially designed for use in holding and placing small elements such as screws, small nails, bolts, etc.

5 The primary object of the invention is to provide a novel tool of this character which may be economically formed from sheet metal strips and embodying novel features of construction for retaining the parts in assembled relation.

10 A further object is to provide a tool of this character which may be easily operated by one hand of the user, and wherein the element when placed in the tool is held between yieldably co-acting jaws permitting ready release of the element when desired.

15 A further object resides in the novel construction wherein the spring for normally urging the movable jaw member toward the stationary jaw member also functions to retain the jaw members against lateral movement.

20 A still further object resides in the novel means for varying the tension upon the jaw operating spring to vary the degree of gripping of the jaws.

25 Other objects and advantages of the invention will be apparent from the following detailed description, taken in connection with the accompanying drawing, forming a part of this specification and in which drawing—

30 Figure 1 is a perspective view of the improved tool.

Figure 2 is a plan view of the tool, with a portion at the handle end in section.

Figure 3 is a longitudinal section thru the tool, with the jaw end in side elevation.

35 Figure 4 is an enlarged fragmentary view part in plan and part in section, and showing an element held in the jaws.

Figures 5, 6 and 7 are transverse sections on the respective lines in Figure 4.

40 Referring to the drawing in detail and wherein like reference characters designate corresponding parts throughout the several views, the tool comprises a main body member 10 and a movable or sliding member 12 having guided movement longitudinally of the member 10.

45 The body member 10 is formed from a length of strip metal which is bent or doubled transversely upon itself adjacent its rear end as at 14 to provide a U-shaped socket having the end wall

50 15. The returned portion 14 as shown is spaced slightly from the shank or main portion 11 of the body member for a distance substantially equal to the thickness of the sliding member 12. The forward end portion of the body member 10 is notched out at one side edge as at 16 for one-half

5 the width of the body member, providing a stationary jaw 17 which is upwardly offset by an angular portion 18 out of the plane of the intermediate main portion 11 for a distance equal to one-half the thickness of the body member as shown in Figures 3 and 7. The working face or edge of the stationary jaw 17 is provided with a small notch 19 to adapt the jaw to better holding of small elements placed in the tool.

10 Referring now to the sliding member 12, the same is also formed from a length of strip metal similar to that of the body member 10 and is adapted to slide longitudinally upon the upper surface of the body member. The rear end of the sliding member 12 extends beneath the returned portion 14 and is bifurcated as shown in Figure 4, providing a terminally opening slot 20 between a pair of side arms 21. Provided adjacent the forward end of the member 12 is a longitudinal guide slot 22 which receives a headed 15

20 guide pin or rivet 23 fixed in the body member 10. This pin and slot connection aside from permitting relative longitudinal movement between the members 10 and 12, also serves to retain the forward portion of the sliding member against 25 lateral movement with respect to the body member. The forward end portion of the sliding member 12 is cut away at one side for one-half the width of the sliding member, providing a

30 movable jaw 24 which is downwardly offset by an angular portion 25 out of the plane of the main portion 13 of the sliding member so as to extend into the notch 16 co-planar with the jaw 17. As

35 shown in Figure 4, the working face or edge of the movable jaw 24 is cut at an angle and extends inwardly and rearwardly from the outer edge of the jaw. With this arrangement of angular working edge, when screws or bolts held between the jaws are being turned, they will be prevented

40 from working or rolling out from between the jaws as will be readily apparent from the showing in Figure 4.

The sliding member 12 is normally spring urged forwardly on the main body member 10 by means of a coil spring 26 whereby the movable jaw 24 is 45 normally urged against the stationary jaw 17 as shown in Figure 2.

45 Formed in the rear end of the main portion 11 is an outwardly pressed rib 27 providing a longitudinal depression or groove 28 at the inner side 50 of the portion of substantially semi-cylindrical shape in cross section and extending to the end wall 15. The returned portion 14 is also formed with an outwardly pressed rib 29 providing a longitudinal depression or groove 30 at the inner 55

side of the portion of substantially semi-cylindrical shape in cross section as shown in Figures 5 and 6. These confronting longitudinal grooves 28 and 30 receive diametrically opposite portions 5 of the coil spring 26 and as shown in Figures 5 and 6, the spring is held against lateral movement thru seating in the grooves. The forward end of the coil spring extends into the slot 20 between the arms 24 and acts upon the sliding 10 member 12 to normally urge the member forwardly. Thus, by bifurcating the end of the sliding member 12 to receive the coil spring 26, the spring also functions to retain the sliding member against lateral movement with respect to the 15 main body member 10.

Means is provided for tensioning the coil spring 26 and this means preferably comprises a disc member 32 fitting in the grooves 28 and 30, and provided with diametrically arranged lugs 33 20 which extend beyond the grooves into the space between the portions 11 and 14 for preventing rotation of the disc member. The disc member 32 is axially screw threaded as at 34 for threaded reception of a tensioning screw 35 having a reduced plain end portion 36 rotatable in an opening provided in the end wall 15 of the main body member 10. The reduced end portion 36 25 forms a shoulder which bears upon the inner side of the end wall 15 as shown in Figure 4, and is provided with a slot for receiving a screw driver or the like for rotating the tensioning screw. The rear end of the coil spring 26 seats 30 against the disc member 32 so that upon movement of the disc member by means of the tensioning screw 35, the tension on the spring may be adjusted so as to vary the gripping force of the jaws 17 and 24. If desired, the tensioning means may be omitted and the rear end of the coil spring 26 permitted to seat against the end 40 wall 15.

The sliding member 12 is provided adjacent its rear portion with an upstanding thumb piece 40 formed by crimping the metal into a fold or ridge.

45 In use, the operator grasps the tool in one hand with the end 15 resting against a suitable portion of the hand and places the thumb upon the projection or thumb piece 40. By exerting a slight rearward pressure on the thumb piece 50 against the tension of the coil spring 26, the jaw 24 will be moved away from the jaw 17 to permit a screw or other element being placed between the jaws. Pressure may now be released on the thumb piece and whereupon the coil spring 55 26 will cause the sliding member 12 to be moved forwardly on the main body member 10 and yieldably grip the screw between the jaws 17 and 24.

60 Changes in detail may be made to the form of the invention as herein shown and described, without departing from the spirit of the invention or the scope of the following claims.

I claim:

65 1. A tool of the class described, comprising a main body member of strip metal formed at one end into a socket and having a flat stationary jaw at its opposite end, a sliding member of strip metal having a longitudinally slotted end 70 fitting in the socket and having a flat jaw at its opposite end co-acting with said stationary jaw, means guiding the sliding member for longitudinal movement on one face of the main body member, and a coil spring in said socket and received in the slotted end of the sliding mem- 75

ber for normally urging the jaw thereof toward the stationary jaw.

2. In a tool of the class described, a main body member having a returned portion at its rear end forming a forwardly opening socket at 5 its forward end, a coil spring retained in the socket, a sliding member having a forked rear end providing arms extending at each side of the coil spring and having a jaw at its forward end normally urged 10 toward the stationary jaw by the coil spring, and guide means for retaining the forward portion of the sliding member against lateral movement with respect to the main body member.

3. In a tool of the class described, a main body 15 member having a socket at one end provided with confronting longitudinal grooves and at its opposite end with a stationary jaw, a coil spring fitting in said grooves, a sliding member having a slot at one end receiving the coil spring and 20 forming arms extending at each side of the spring, a jaw at the opposite end of the sliding member and normally urged toward the stationary jaw by the coil spring, and a pin and slot connection between the main body member and 25 sliding member adjacent the jaw carrying ends thereof.

4. In a tool of the class described, a main body member having a socket at one end provided with confronting longitudinal grooves and at its 30 opposite end with a stationary jaw, a coil spring fitting in said grooves, a sliding member having a slot at one end receiving the coil spring and forming arms extending at each side of the spring, a jaw at the opposite end of the sliding 35 member and normally urged toward the stationary jaw by the coil spring, means for varying the tension on the coil spring and a pin and slot connection between the main body member and sliding member adjacent the jaw carrying ends 40 thereof.

5. In a tool of the class described, a main body member formed from strip metal and providing a socket at its rear end and a stationary jaw at its forward end, a sliding member formed 45 from strip metal and having a forked rear end fitting in said socket and a jaw at its forward end co-acting with the stationary jaw, a coil spring retained against lateral movement in the socket and engaging in the forked end of the 50 sliding member for normally urging the sliding member forwardly on the main body member, a pin and slot connection between the forward portions of said members, and a thumb piece formed on the sliding member for moving the 55 same rearward against the tension of the spring.

6. In a tool of the class described, a main body member of strip metal having a notch in one side edge providing a rearwardly facing jaw, a sliding member of strip metal movable longitudinally on the body member and cut away at one side edge to provide a forwardly facing jaw, said jaws being offset in co-planar relation, and means yieldably urging the sliding member jaw toward the jaw of the main body 65 member.

7. In a tool of the class described, a strip metal body member having one end portion turned upon itself forming a socket and provided at its opposite end with a jaw, confronting 70 semi-cylindrical shaped grooves formed in the socket, a coil spring fitting in said grooves, a strip metal sliding member having a slot at one end receiving the coil spring and providing a pair of arms extending along opposite sides of 75

the spring, and having a jaw at its opposite end normally urged against the first mentioned jaw by said coil spring, a pin and slot connection between the forward portions of said members, a tensioning member held against rotation in the socket and forming a seat for one end of the coil spring, and means for adjusting the tensioning member for varying the tension of the coil spring.

5 10 8. In a tool of the class described, a strip metal body member notched out at one edge adjacent its forward end to form a jaw, said jaw being offset out of the plane of the body member for a distance equal to one-half the thickness of the member, a strip metal sliding member longitudinally movable on the body member and cut away at one edge and at its

forward end to form a jaw, said last mentioned jaw being offset into said notch in co-planar relation to the first mentioned jaw, and means normally urging the sliding member forwardly on the body member.

9. In a tool of the class described, a body member formed of strip metal and having a rearwardly facing jaw at its forward end, a sliding member formed of strip metal and having a forwardly facing jaw at its forward end confronting the jaw of the body member, a pin and slot connection between the forward portions of the members, a socket formed at the rear end of the body member, and a coil spring in the socket and normally urging the sliding member forwardly on the body member.
